Attorney.

UNITED STATES PATENT OFFICE.

HARRY GARABEDIAN, OF PROVIDENCE, RHODE ISLAND, ASSIGNOR TO REX MANUFACTURING COMPANY, A CORPORATION OF RHODE ISLAND.

BRACELET.

1,176,140.

Specification of Letters Patent. Patented Mar. 21, 1916.

Application filed November 29, 1915. Serial No. 63,965.

To all whom it may concern:

Be it known that I, HARRY GARABEDIAN, a subject of the Sultan of Turkey, residing at Providence, in the county of Providence, 5 and State of Rhode Island, have invented certain new and useful Improvements in Bracelets, of which the following is a specification.

My invention relates to what are known 10 as guard bracelets, that is to say bracelets wherein a guard member is arranged to connect the bracelet wings when the latter are distended, so that the bracelet will not completely disengage the wrist, and the wings 15 will not be excessively distended, and means are afforded for guiding the free ends of the wings to and from each other.

The essential objects of my invention are 20 to effect the usual ends sought in this type of bracelet: to afford a maximum degree of strength and a minimum of weight in the guard member; to afford exceptionally stiff and resilient engaging means for the ends 25 of the guard member; to avoid loops and the use of solder, and attain these ends in a guard capable of being cut out of a blank, and cheaply.

To the above ends my invention consists 30 in such parts and combinations of parts as fall within the scope of the appended claims.

In the accompanying drawings which 35 form a part of this specification, Figure 1 is a top plan elevation of my new bracelet, Fig. 2, a longitudinal section of the adjacent ends of the same in a closed position, Fig. 3, a similar section in open position, Figs. 4 and 5 front and plan elevations of the guard member, and Figs. 6 and 7, sections on lines 6—6 and 7—7 respectively of 40 Fig. 3.

Like reference characters indicate like parts throughout the views.

My invention in its present form of embodiment comprises the usual hollow wings 45 9 and 10 hinged at 11 in any usual manner.

Fixed by solder or otherwise in the wings are caps 12 and 13 respectively. The former is located a short distance in from the end 50 of the wing 9, while the latter cap projects slightly from the end of wing 10. There is an opening 14 in the upper wall of cap 12, and an opening 15 in alinement therewith in the wing 9, to accommodate a thumb

piece. The cap 13 has an oblong opening 16 55 in its front wall to receive one end of a guard member; and the cap 12 has a like opening 17 to receive the other end of the member.

The guard member comprises an oblong 60 frame 18 stamped or cut out of thin sheet metal. The material while stiff is sufficiently thin to afford resiliency in its projecting portions. The frame is shown in detail in Figs. 4 and 5, and comprises two 65 flat parallel rods 19 and 20 provided in their intermediate portions with integral flat cross pieces 21 and 22. At one end the rods have outwardly directed lugs 23. The portions 25 and 26 of the rods 19 and 20 respectively 70 between the brace 22 and the lugs 23 have such a degree of resiliency as to permit some compression toward each other. The opposite free end portions 28 and 29 of the rods 19 and 20 respectively are also resilient and 75 compressible toward each other. Near the end of portion 29 are depending shoulders 31 with a space 32 therebetween. These shoulders embrace the lower margin of the cap 12 which rests in the space 32 and retain 80 the guard member 18 in fixed longitudinal relation to the wing 9. This engagement is effected by originally compressing the portions 28 and 29 of the rods as they pass into the cap 12, and then releasing them. 85

Upon the free portion 28 is a shoulder 34 provided with an inclined face 35. Adjacent this shoulder is a second shoulder 36. Beyond the latter shoulder near the end of the portion 28 is a projection 37 extending 90 loosely through the openings 14 and 15 and projecting exterior of the bracelet wing. This projection is for operating the arm portion 28, and in the present instance has fixed to its end by swaging a cap 38 provided with 95 a nail cavity 39 in its end.

The operation of the bracelet is thus: In closed or locked position the parts are as shown in Fig. 2. To release the parts the projection 37 is depressed, bringing the 100 shoulder 34 down into the plane of the opening 16 of the cap 13, and then the wing 10 is drawn outwardly till it is checked by the stop lugs 23 in the position shown in Fig. 3.

The parts are relocked by bringing the 105 wings 9 and 10 together, the cap 13 riding over the inclined face 35 until the rear of the shoulder 34 is reached, whereupon the re-

siliency of the member 28 forces the shoulder up locking the cap 13 between the shoulders 34 and 36.

What I claim is:—

- 5 1. In a bracelet, the combination of hollow wings, one of said wings being provided with a perforation, caps in the wings, a guard member comprising a body, compressible arms on one end of the body, means on one arm for engaging one cap, a shoulder on the other arm within said cap, said cap-engaging means and shoulder being out of alinement with each other, a projection on 50 the second arm in the perforation, arms upon the other end of the body extending through the other cap, and lugs upon the last mentioned arms within the second cap.
- 10 2. In a bracelet, the combination of hollow wings, one of said wings being provided with a perforation, caps in the wings, a guard member comprising a body, compressible arms on one end of the body, means on one arm for engaging one cap, a shoulder on the other arm within the cap out of alinement with said cap engaging means, a projection on the second arm in the perforation, and resilient arms on the other 55 end of the body extending within the second cap, and having means engageable within said second cap.
- 15 3. In a bracelet, the combination of hollow wings, one of said wings being provided with a perforation, caps in the wings, a guard member comprising a body, resilient arms on one end of the body, means on one arm for engaging one cap, an inclined shoulder on the other arm out of alinement with said cap engaging means and in the path of 60 said cap, the incline of said shoulder serving to guide the cap beyond the shoulder as the wings are brought to closed position, a projection on the second arm in the perforations, and arms on the other end of the body extending within the second cap.
- 20 4. In a bracelet, the combination of hollow wings, one of said wings being provided with a perforation, caps in the wings, a guard member comprising a body, resilient arms on one end of the body, means on one arm for engaging one cap, a shoulder on the other arm within the cap out of alinement with said cap engaging means, with an inclined face leading to said shoulder to compress said arm as the wings are moved together, a projection on the second arm in 65 the perforation, compressible arms on the other end of the body, and lugs on the last mentioned arms extending through the second cap.
- 25 5. In a bracelet, the combination of hollow wings, one of said wings being provided with a perforation, caps in the wings, a guard member comprising a body, resilient arms on one end of the body, means on one arm for engaging one cap, a shoulder on the other arm within the cap out of alinement with said cap engaging means, with an inclined face leading to said shoulder to compress said arm as the wings are moved together, a projection on the second arm in 70 the perforation, compressible arms on the other end of the body, and lugs on the last mentioned arms.
- 30 6. As a new article of manufacture a guard member for hollow bracelets formed of a single piece of metal comprising side bars, cross bars integral with the side bars, resilient arms integral with the side bars at one side of the cross bars, engaging lugs on 75 one arm, a beveled shoulder on the other arm out of alinement with said lugs, a projection on the second arm, resilient arms integral with the side bars located at the other side of the cross bars, and lateral lugs on the last 80 mentioned arms.

low wings, one of said wings being provided with a perforation, caps in the wings, a guard member comprising a body, compressible arms on one end of the body, means on one arm for engaging one cap, a shoulder on the other arm within said cap, said cap-engaging means and shoulder being out of alinement with each other, a projection on 50 the second arm in the perforation, arms upon the other end of the body extending through the other cap, and lugs upon the last mentioned arms within the second cap.

5. In a bracelet, the combination of hollow wings, one of said wings being provided with a perforation, caps in the wings, a guard member comprising a body, resilient arms on one end of the body, means on one arm for engaging one cap, a shoulder on the other arm within the cap out of alinement with said cap engaging means, with an inclined face leading to said shoulder to compress said arm as the wings are moved together, a projection on the second arm in 65 the perforation, compressible arms on the other end of the body, and lugs on the last mentioned arms extending through the second cap.

6. As a new article of manufacture a guard member for hollow bracelets formed of a single piece of metal comprising side bars, cross bars integral with the side bars, resilient arms integral with the side bars at one side of the cross bars, engaging lugs on 70 one arm, a beveled shoulder on the other arm out of alinement with said lugs, a projection on the second arm, resilient arms integral with the side bars located at the other side of the cross bars, and lateral lugs on the last 75 mentioned arms.

In testimony whereof I have affixed my signature.

HARRY GARABEDIAN.
